UNITED STATES PATENT OFFICE.

EDWARD A. LESLIE, OF BROOKLYN, NEW YORK

HEAT GENERATION FROM LIQUID FUEL.

Application filed November 19, 1923. Serial No. 675,770.

To all whom it may concern:

Be it known that I, EDWARD A. LESLIE, a citizen of the United States, and resident of Brooklyn, in the county of Kings and State 5 of New York, have invented certain new and useful Improvements in Heat Generation from Liquid Fuel, of which the following is a specification.

This invention relates to heat generation 10 from liquid fuel. Its general object is to conserve heat in the liquid fuel used for generating heat and to utilize it more effectively than heretofore with attendant advantages stated below and forming particular objects of the invention. By its employment, heat may be generated by use of a minimum of oxygen in the burner, so that the burning out of the constructive materials is minimized; some of this oxygen is 20 derived from the waste gaseous products of combustion and the remainder from the atmosphere, and means are provided to vary the relative proportions of the two so that at all times the proper proportions of waste 25 gas and of air may be utilized to obtain an efficient combustion of the fuel. The invention is shown applied to a water tube boiler.

In the accompanying drawings forming a 30 part hereof and illustrating the principle of the invention in the best mode now known to me of applying that principle.

Fig. 1 is a top plan view of a water tube boiler setting and of parts embodying this 35 invention; and Fig. 2 is a vertical section in the direction of the length of the tubes, at line 2-2 of Fig. 1.

In the drawings, 1 indicates the boiler setting; 2 boiler tubes; 3 a combustion chamber in the lower front corner portion of the setting; 4 the usual bridge wall which partially separates the combustion chamber from a rearward space 5 under the rearward portion of the boiler tubes; 6 the usual top or arch wall of the combustion chamber; 40 45 and 7 the usual upstanding, rearward extension of the wall 6 through which the tubes 2 pass upwardly and forwardly. Spaced above the upper end of wall 7 and also above the tubes is the usual drum 8. The 50 usual space between the top of wall 7 and the drum for travel of gaseous products of combustion from the space 5 forwardly and upwardly is indicated at 9. The usual space into which the upper forward ends of the 55 tubes and the front portion of the drum extend, being the upper front portion of the

setting above the arch wall and forwardly of the wall 7 is indicated as a space 10 from the upper wall of which a flue 11 extends upwardly. The gaseous products of combustion travel from the combustion chamber 3 through a communication chamber which receives these products as they pass over the bridge wall, whence they enter the portion 5 of this communication chamber, 60 65 pass upwardly in a further portion thereof between the wall 7 and the back wall of the setting, and then forwardly again toward the portion 10 of this communication chamber, and finally pass upwardly into and 70 through the stack or flue 11. This course through the combustion and communication chambers and the flue is indicated by arrows on the drawing.

In accordance with this invention, a gaseous mixture is taken into a primary heater 12 located in the lower portion of the flue 11 through an air intake pipe 13, the upper outer end of which is open to the atmosphere. Atmospheric air is sucked through 80 an air control valve 13^a into the pipe 13 by a suction blower 14 operated by a motor M. A bleeder pipe 15 provided with a control valve 16 leads to the pipe 13 from a downwardly projecting hood 17 located 85 within the flue, the bleeder pipe being connected with the pipe 13 between the air admission valve 13^a and the blower. Gaseous mixture passing through the blower is forced by the blower through the latter's 90 discharge pipe 18 into the primary heater 12. This primary heater is provided with a discharge pipe 19 which is shown outside 95 of the upper wall of the setting and communicates with a downwardly extending pipe 20 which is shown outside of a side wall of the setting and which communicates with a secondary heater 21 in the upper, rearward portion of the combustion chamber adjacent the space above the bridge wall 4 and in the 100 path of the hot gaseous products of combustion, travelling rearwardly over and past the bridge wall. The location of the pipes 19 and 20 is one of structural convenience. Altho shown outside the setting, they may 105 be inside of it, if structural conditions warrant.

The secondary heater 21 discharges into the top of a carburetor casing 23 located outside the setting. A fuel oil supply pipe 24 also discharges into the upper portion of the carburetor casing above and over an

upper, horizontal baffle plate 25 within the casing. The gaseous mixture from the pipe 22 initially mixes with oil vapor in the space above the upper baffle plate and travels 5 in a downward direction over the free edge 26 of the upper baffle plate to a lower baffle plate 27; thence over its free edge to the bottom wall 28 of the casing. The bottom space in the carburetor casing is in communication with a burner pipe 29 which leads into the combustion chamber through an opening in a plug 31 of refractory material inserted in an opening 30 in the wall of the setting. The plug is formed with an 10 observation and ignition port 32. In the form shown, the carburetor is constructed to prevent admission of atmospheric air into it and the combustion chamber is constructed to prevent admission of atmospheric 15 air into it except through the observation and ignition port 32, the fire-box end of which is adjacent the end of the burner pipe. Various changes may be made in the construction without departure from this invention. 20

In operation, the hood 17 catches some of the gaseous products of combustion ascending the flue and directs their flow under the influence of the suction blower through the 25 bleeder pipe 15 when its valve 16 is more or less open. Thus such gaseous products of combustion are brought into the descending current of air and burnt products of combustion in a gaseous condition, such as carbon dioxide, etc., are introduced into the current of air passing the air admission valve 13. The mixture flows to the primary heater wherein the temperature of the mixture is brought usually to from 300° F. to 40 600° F., depending, of course, on the temperature of the waste gases flowing through the stack or flue, and the regulated opening of valve 16. The mixture then passes from the primary heater through the pipe 19 into the pipe 20 the lower end of which is about 45 level with the secondary heater 21, and passes through the side wall of the setting into communication with that heater, wherein the temperature of the mixture is further increased from about 600° F. to 1100° F., owing to the exposure of the secondary heater where the gaseous products of combustion pass the bridge wall into the space 5 and upwardly into contact with the tubes and up to the stack. The mixture at this 55 high temperature is introduced into the carburetor.

The particular objects of the invention are:

60 First, to utilize waste heat in the stack for preheating the air initially introduced into the system. Second, to dilute the pre-heated air with waste gases from the stack and thereby reduce the flame temperature in the combustion chamber to a safe point so

that it will not destroy brick work or linings of the combustion chamber or adjacent parts. Third, to make the combustible mixture rich or lean in oxygen required for the support of combustion by providing a control valve 70 for the bleeder pipe and an air admission control valve for the approximate exclusion of atmospheric air adjacent the flame; and fourth, to produce a construction in which the flame is produced at the end of an ordinary, open ended pipe, as shown, without necessity of using any special burner. 75

The foregoing heat generating invention may be embodied in various structures for various kinds of heating, the invention not 80 being limited to steam generation, although particularly valuable for that purpose.

What I claim is:

1. In a fluid fuel furnace, a main casing comprising a combustion chamber substantially sealed against the admission of atmospheric air when in use, and a communication chamber for the travel of gaseous products of combustion from the combustion chamber; a stack to receive said gaseous 90 products; an air supply pipe having an air admission control valve and a suction blower, a conduit to lead a portion of the outflowing hot gaseous products of combustion from said stack into said air supply pipe between said valve and said blower for mixture with the intaken air, a primary heater located in the stack to be heated by the escaping hot products of combustion, a pipe to convey the hot mixture from the said blower to said primary heater; a secondary heater in the path of the hot products of combustion and adapted to further increase the temperature of said mixture; a pipe communicating with said primary and said secondary heaters; a carburetor sealed against the atmosphere and having a fuel oil inlet and a mixing chamber; a pipe communicating with said secondary heater and said carburetor; and a burner pipe leading from said carburetor and adapted for flame production within said combustion chamber. 105

2. In the structure and combination set forth in claim 1, a bridge wall constituting the rear and an arch wall constituting the top of said combustion chamber, an upstanding wall with its top spaced from the upper wall of the casing and connected to said arch wall, said walls defining the said communication chamber for the travel of the gaseous products of combustion; said stack being located at the upper front end of said communication chamber; and a steam generating apparatus located in said communication chamber and exposed to said hot gaseous products of combustion. 120

3. In a fuel oil burning apparatus for heating water, the combination of a boiler setting substantially sealed against the admission of the atmosphere, a combustion 130

chamber in said setting, a stack mounted on said setting, a communication chamber conducting the hot products of combustion from said combustion chamber to said stack: 5 water-heating apparatus within said boiler setting and exposed to said hot products of combustion; an air intake, a primary heater located in the path of the escaping hot products of combustion, a secondary heater located 10 within the combustion chamber, conduits forming communication from said air intake through said primary heater to said secondary heater, and located partially exterior to said boiler setting; an exterior carburetor, a fuel intake pipe for said carburetor, a pipe connecting said secondary heater and said carburetor, and a burner pipe leading the combustible mixture from 15 said carburetor to said combustion chamber.

20 4. In a fuel oil burning apparatus, a boiler setting, a stack mounted thereon, an air intake, a suction blower receiving air

from said intake, a bleeder pipe to receive waste gaseous products of combustion from said stack and deliver them to said suction blower, a primary heater to receive the gaseous mixture from said blower, an exterior carburetor, a fuel oil intake for said carburetor, and a pipe connecting said primary heater and said carburetor and located partially in the path of the hot products of combustion and partially exterior to said boiler setting. 25

5. In the combination set forth in claim 4, an air control valve to control the admission of air to said blower. 30

6. In the combination set forth in claim 4, means to vary the relative proportions of atmospheric air and of waste products of combustion admitted to said blower. 35

Signed at New York city, in the county of New York and State of New York, this 7th day of November A. D. 1923.

EDWARD A. LESLIE.
